UNITED STATES PATENT OFFICE.

NYLA Q. KELSO, OF OKLAHOMA CITY, OKLAHOMA, ASSIGNOR OF ONE-HALF TO JOHN A. SEMKE, OF OKLAHOMA CITY, OKLAHOMA.

SASH-OPERATING DEVICE AND LOCK.

Application filed October 16, 1923. Serial No. 668,922.

The object of this invention is the provision of means whereby a window sash or the like is permitted to slide in its casing, and to be locked in either its raised, partly raised or closed position.

To the attainment of the foregoing, the invention consists in the improvement as hereinafter described and definitely claimed.

In the drawings:—

10 Figure 1 is an elevation with parts in section showing the elements constituting the improvement so arranged as to permit of the free sliding of a window sash.

15 Figure 2 is a similar view showing the sash locked against movement in either direction.

Figure 3 is a sectional view on the line 3—3 of Figure 1.

20 Figure 4 is a sectional view similar to Figures 1 and 2 showing the sash locked to prevent the downward but to allow the upward movement thereof.

Figure 5 is a fragmentary perspective view of a stile of the sash.

25 Figure 6 is a sectional view on the line 6—6 of Figure 4.

Figure 7 is a perspective view of the slidable member which influences the corrugated wheel.

30 In the drawings the numeral 1 designates a slidable sash, and 2 a sufficient portion of the casing in which the sash moves.

In the present instance one or both of the vertical stiles of the sash has its outer 35 edge grooved longitudinally and seated in the groove there is a rack bar preferably in the nature of a transversely corrugated strip 3. The rack bar is, of course, secured in the groove.

40 The casing 2 has a pocket let in the side thereof in which the sash 1 slides, and in this pocket there is secured a casing broadly indicated by the numeral 4. The casing has its front open and its rear wall arranged at 45 opposite outward inclinations toward its center, and its said central portion rounded, as at 5. The open face of the casing is closed by a plate 6 which is centrally provided with a substantially rectangular opening 7 arranged opposite the grooved stile of the sash 1.

50 Freely arranged in the casing and projecting through the opening 7 in the face plate thereof, there is a wheel 8 that is provided 55 with peripheral teeth or corrugations 9.

The wheel 8 normally rests on the inwardly curved head 10 of a rack 11, and the teeth of the rack are engaged by a toothed wheel 12. The toothed wheel is, of course, journaled in the casing, and one of its shafts or 60 trunnions is provided with a socket 13 that aligns with a round opening 14 through the side of the casing. Through this opening there is designed to be inserted a key (not shown) having a squared end to be received 65 in the squared socket 13 whereby the wheel 12 may be turned to move the head carrying rack 11 vertically in the casing. When the rack is moved to bring its head 10 to the position illustrated in Figure 1 of the 70 drawings the toothed wheel is so arranged as to permit of the free sliding of the sash in either direction. When the rack member 11 is further moved in a vertical direction, as disclosed in Figure 2 of the drawings, the 75 wheel 8 will bind against the upper inclined wall 15 in the back of the casing so that movement of the sash in either direction is prevented. When the rack is lowered, as disclosed in Figure 4 of the drawings, the 80 toothed wheel 8 is in binding engagement with the lower inclined wall 16 of the casing and the wedging engagement therebetween will prevent the turning of the wheel and the lowering of the sash. The sash, 85 however, can be raised when the parts are in this position.

With my improvement, the employment of the usual weights is entirely dispensed with and the sash is arranged for free sliding in the casing. However, with my improvement the sash may be locked in either its raised, partly raised or lowered position. The construction is comparatively simple, 90 may be cheaply manufactured, marketed and installed, and while I have illustrated and described a preferred embodiment thereof it is to be understood that I may make such changes therefrom as fall within the scope of what I claim.

Having described the invention, I claim:—

1. A means for locking and controlling the movement of a vertically slidable member which includes a guide for the member, a casing in the guide having its rear wall inclined inwardly from the center thereof, a toothed wheel in the casing projecting therethrough and contacting with the slidable member and normally gravitating to the bottom of the casing for frictionally engag- 105 110

ing the rear wall thereof and the slidable member to prevent the movement of the slid-
able member in one direction, vertically
adjustable means underlying and normally
5 supporting the toothed wheel whereby said
wheel may be moved to the center of the
casing and free from frictional engagement
with the casing and with the slidable mem-
ber or to be further moved for contacting
10 engagement with the upper portion of the
casing for the slidable member for holding
said slidable member from vertical move-
ment in either direction.

2. The combination with a vertical slid-
able member and a guide therefor, of a cas-
ing let in the guide and having an open face
opposite the slidable member, the rear wall
of the casing being rounded and from thence
being inclined inwardly in opposite direc-
20 tions to the top and bottom thereof, a grav-

ity influenced toothed wheel in the casing
normally engaging the lower inclined wall
thereof and the slidable member for holding
the said slidable member from movement in
one direction, a headed rack having a toothed 25
shank in the casing and underlying the
wheel, a key operated wheel engaging the
rack and designed when rotated, to raise the
said rack to bring the toothed wheel in the
center of the casing and out of frictional 30
engagement with either the casing or the
slidable member or to further move the said
toothed wheel to cause a binding action be-
tween said wheel, the upper portion of the
casing and the slidable member or for hold- 35
ing the slidable member from movement in
either direction.

In testimony whereof I affix my signature

NYLA Q. KELSO.
